Original application December 22, 1943, Serial No.
515,223. Divided and this application Decem-
ber 30, 1944, Serial No. 570,694

7 Claims. (Cl. 166—14)

1

This invention relates to a casing head and it is a general object of the invention to provide an improved, simple, inexpensive and practical casing head construction for use on wells.

This application is a division of my co-pending application entitled "Casing Head," Serial No. 515,223, filed December 22, 1943, now Patent No. 2,469,772, granted May 10, 1949.

A wide variety of structures have been proposed and used in the finishing of wells, these devices being commonly termed casing heads. In many situations it has been found desirable and practical to use certain welded constructions in such situations. However, such constructions have presented certain limitations and difficulties.

It is an object of the present invention to provide a casing head construction particularly applicable for use where welded constructions are employed, it being a feature of the invention to provide a head wherein welded joints are employed so that they are most efficient, dependable, and are accessible.

Another object of my invention is to provide improvements in the base construction of a casing head. By my present invention I provide a base applicable to a casing head so that it not only forms an effective support for the head but also a tie between the head and casing. Another feature of the base provided by my invention is the construction whereby the base can be effectively applied to the head without in any way interfering with the other parts of the head which must be reached.

A further object of the present invention is to provide improvements in a casing head of the character referred to which results in a compact arrangement of parts and which will accommodate an ordinary or standard companion flange of a fitting, or the like, that may be applied to the head. Heretofore in welded head constructions it has been common to employ arrangements and combinations of parts which made special companion flanges necessary on parts to be attached to the head.

The various objects and features of my invention will be fully understood from the following detailed description of a typical preferred form thereof, throughout which description reference is made to the accompanying drawings, in which:

Fig. 1 is a side view of a head construction embodying the present invention, the parts shown at the left of the figure being in section and those at the right of the figure being in elevation. Fig. 2 is a perspective view of the shoulder for the inner casing, showing it inde-

2

pendent of the casing and showing it immediately above Fig. 3 wherein is shown a perspective view of the support for the shoulder, the rotative positions of the parts shown in Figs. 2 and 3 being such as to cause the shoulder to be supported by the support upon being lowered into it.

The construction shown in the drawings involves, generally, a body 10 which is the principal part of the head and which is adapted to be applied to an outer casing 11, a base 12 that may be used in connection with the body 10 and casing 11, a shoulder means 13 adapted to be applied to an inner casing 14 arranged through the body 10, a support 15 carried in the body 10 to support the shoulder 13, packing means 16 for sealing between the inner casing 14 and the body 10 and various other features, the details of which will be hereinafter described.

The body 10 is adapted to be secured to the upper end of the casing 11 to project slightly above the casing and in its preferred form it has an annular skirt or depending sleeve portion 17 which is tubular in form and depends downwardly to receive the upper end portion of the casing 11. The term "slightly above the casing" refers to a distance substantially as shown in the drawings as distinguished from an infinite distance such as might be represented by a pipe or like structure. A bore or cavity 18 extends downwardly into the body from its upper end to accommodate other parts, as will be hereinafter described. The cavity 18 terminates in a seat 19 which carries the support 15. A flange 20 is provided at the upper end of the body to project radially beyond the other parts and to serve as a means whereby the body can be coupled with other parts or fittings that may be applied to the head. The body has one or more fluid connections 21 located immediately below the flange 20 and communicating with the cavity 18.

The skirt 17 at the lower part of the body 10 has a bore 22 to receive the upper end portion of the outer well casing 11. The bore terminates in a suitable stop shoulder 23 which limits the insertion of the casing into the skirt. In accordance with the present invention I employ welding to join or connect the body 10 and casing 11 and, as a feature of the invention, I employ two entirely independent seams of welding, both of which extend entirely around the connected parts and each of which is, in and of itself, a secure, dependable connecting means.

One of the welded connections is an exterior weld and is provided at 24 and joins the lower end of the skirt or sleeve 17 with the exterior of the

well casing 11. It will be seen from the drawings that the lower end of the sleeve 17 is fully exposed at the exterior of the head so it can be readily reached with standard welding equipment. The other welded connection is an interior weld and is provided at 25 between the upper end of the well casing 11 and the interior of the skirt 17. Both welds extend continuously and entirely around the casing and skirt.

In accordance with my invention I form the skirt 17 so that it has a thin or light wall. It is preferred to form it so that its wall is about equal in thickness to that of the casing 11. This proportioning of the skirt 17 is important as it greatly facilitates the obtaining of proper welds 24 and 25. Heretofore, in constructions of this general character, attempts have been made to weld casing to bodies or heads of substantial mass and the results have not been altogether satisfactory. Parts such as a casing head or body are usually made of materials that do not lend themselves readily to welding, and if an attempt is made to weld a thin-walled part to a thick-walled body the welding difficulties are aggravated. By providing a thin-walled skirt 17 I am able to obtain dependable and satisfactory welds 24 and 25.

It is preferred, in practice, to provide one or more openings 26 in the skirt 17 to communicate with the bore 22 between the welds 24 and 25 so that tests can be made to determine whether or not the welds are tight. Tests can be made at any time through the openings 26 and if necessary suitable plastic packing can be inserted through the openings 26 to seal between skirt 17 and well casing 11 to eliminate any slight leakage that may occur should the welds prove defective. To facilitate the application of packing an annular channel 27 may be provided between the skirt and casing to carry packing.

The base 12 provided by my invention is in the nature of an attachment to be applied to the other parts and may or may not be used as circumstances require. A feature of the present invention is the fact that the base is a simple construction readily applicable to the other parts and when applied serves as an effective tie between the body 10 and casing 11.

In its preferred form the base 12 includes a base plate 30 which may be a flat member arranged around the casing 11 and designed to rest on the floor of the cellar or on any other suitable support. The plate has a central annular portion the opening of which passes the casing 11. I prefer to fit the central annular portion of the base plate 30 closely around the casing 11 and to provide said portion of the plate with a top or upper end suitable for the reception of welds 31 between the base plate and the casing 11. Through this construction the base plate 30 is independently and effectively joined with the casing 11 at the desired point. I further provide upstanding ribs 32 on the peripheral portion of the base plate 30 which projects radially from the central annular portion and which may be thinner than the central annular portion as clearly shown in Fig. 1. The ribs are designed to engage under overhanging or downwardly facing parts of the body 10 and their upper ends are joined with such parts by welding 33. In the particular construction illustrated some of the ribs 32 engage under the flange 20 and are welded thereto while others engage under the flanges 21 and are welded thereto.

In accordance with my present invention the

ribs 32 are spaced outwardly from the skirt 17 of the body 10 leaving a substantial space 18 between adjacent ribs and the skirt. This construction allows free access entirely around the skirt 17 to facilitate convenient welding of the lower end of the skirt to the casing 11.

In practice the base construction hereinabove described can be welded to the body 10 in a shop when it is known that the base is desired, in which case the welds 31 are the only operations required at the well, or, if convenient, the body 10 and base 12 can be handled as separate parts and the welds 31 and 33 can both be made at the well.

The shoulder means 13 is normally located within the body 10 and is an element which is secured to the inner casing 14. The shoulder means 13 is preferably in the form of a split ring having two sections A and B. The sections 20 A and B are divided longitudinally of the head and form halves of an annular shoulder to be engaged around the casing 14. I prefer to secure the sections A and B in assembled position through welding. In practice I provide an upwardly projecting flange 35 on the means 13 to be welded to the exterior of the casing 14. The upper edge of the flange is preferably collapsed to materially lengthen the welded connection and thereby add to its strength.

The shoulder means 13 is fixed on the inner casing 14 so that when the casing 14 is in the desired vertical position in the body 10 it is located at or in a position to be supported by the support 15 carried on the seat 19. The shoulder means 13 is proportioned to freely pass through the body 10 and it may also be made to pass through the casing 14 if desired. The exterior or outer face 36 of the shoulder means 13 is tapered to cooperate with the support 15. As shown in the drawings the exterior of the shoulder 13 is tapered downwardly and inwardly.

The support 15 is provided to carry the shoulder means 13 and is in the form of an annular ring designed to rest on the seat 19 in the body 45 10 and its bore or inner surface 37 is tapered to correspond to the surface 36 of the shoulder and is adapted to receive the shoulder.

The means 15 may be a split ring construction to facilitate insertion into or removal from operating position in the body around parts arranged in the body. In the case illustrated the seat 19 is shown downwardly and inwardly tapered and, therefore, the exterior of the support 15 has a downwardly and inwardly tapered part 38 designed to fit the seat 19.

Longitudinal channels 40 are formed in the inner portion of the support 15 and similar channels 41 are formed in the exterior of the shoulder 13. The channels 40 and 41 are made of sufficient circumferential extent and are made deep enough so that the shoulder 13 can be rotatively positioned with reference to the support 15, so that the shoulder can be passed through the support. When the shoulder and support 65 15 are rotatively related, as shown in Figs. 2 and 3, the exterior faces 36 of the shoulder will rest on the interior faces 37 of the support, but the parts can be rotated to a position where the faces 36 and 37 will not register but rather the channels 40 and 41 will allow free passage of the shoulder through the support. It is to be noted that when the surfaces 36 and 37 of the shoulder and support are fully engaged the channels 40 and 41 register or are in corresponding 70 75 positions so that there are vertical

channels through the structure formed by the shoulder and support, so that fluid from the casing 11 can pass upwardly through the structure and readily discharge from the body 10 through the fluid connections 21, the openings 43 of which open into the cavity 18 at a point above the seat 19 which carries the support 15.

A lock means normally holds the shoulder 13 against rotation relative to the support 15 such as would disengage the surfaces 36 and 37. The lock means may include one or more arms 45 projecting radially from the shoulder 13 to engage between lugs 46 projecting upwardly from the support 15.

It will be noted from the drawings that the arms 45 not only serve to cooperate with the lugs 46 to prevent rotation of the shoulder 13 relative to the support 15 but that they will also serve to prevent passage of the shoulder 13 through the support. When it is desired to move the shoulder through the support the arms 45 are removed by disengaging the screws 47.

The packing means 16 may include a plate 53 designed to rest on the inner peripheral portion of the body flange 20 having an opening 51 receiving the upper end of the casing 14. A recess 52 is provided in the plate 51 to carry packing and a port 54 extends from the recess 52 to the marginal portion of the plate 50 so that a test can be made to determine whether or not the packing in the recess is leaking or so that plastic packing material can be inserted if desired. In the case illustrated spaced bodies of packing 55 are carried in the recess at either side of a spindle ring 56 and a gland 57 is carried by the plate operable by screws 58 to compress the packing in the recess 52. It is to be noted that the plate 50 is shaped so that it extends downwardly into the cavity 18 in the body 10 and that the various parts just described are arranged and related so that they are all confined between the upper and lower extremities of the plate 50.

The plate 50 is preferably sealed to the body 10 by a sealing ring 59 arranged between the plate and the top of the flange 20. In a similar manner the upper end of the plate 50 may be sealed to the flange 60 of a fitting applied to the head through a sealing ring 61, as shown in Fig. 1.

In practice various fittings or attachments may be applied to the head. In the drawings I have shown a typical fitting applied to the head and including the companion flange 60 which is adapted to be secured to the flange 20 of the body 10 by bolts 65. Particular attention is called to the fact that the companion flange 60 is a plain, straight flange and that the construction which I have provided makes it unnecessary to recess or specially form the flange 60 to accommodate other parts.

In practice the body 10 is applied to the casing 11 through the exterior and interior welds 24 and 25 and, if desired, the base 12 is applied to the body and to the casing 11. The support 15 is arranged in the body 10 and the shoulder 13 is assembled around the upper end portion of the casing 14, and is then welded at the desired point along the casing 14. The casing 14 is trimmed or cut so that a suitable length thereof projects above the shoulder 13 to receive the packing means 16.

During normal operation the faces 36 and 37 of the shoulder and support are in cooperative engagement and the lock means hold the parts in that position. Fluid from the casing 11 is

free to flow up through the registering channels 40 and 41 to discharge through the fluid connections 21. The packing means 16 is held in place in connection with the body 10 by means of the bolts 65 which clamp the flange 60 toward the flange 20, the plate 50 being clamped between the flanges and the packings 59 and 61 serving to prevent leakage between the plate 50 and the flanges. The packing means 16 is made tight around the upper or projecting end of the casing 14 and serves to prevent leakage between the casing and the plate.

When it is desired to disengage the inner casing from the head or body 10 for any reason, as for instance, when the well is being dismantled, a spear or other tool may be inserted in the upper end portion of the inner casing 14 and the arms 45 being removed the shoulder 13 can be lifted slightly from the support 15 whereupon the support can be freely rotated so that the surfaces 36 and 37 are disengaged and the channels 40 and 41 positioned to allow the shoulder 13 to pass through the support 15. This operation can be performed either to allow the casing 14 to be lowered in the head or to allow the body 10 to be lifted up off the casing 14.

Having described only a typical preferred form of my invention, I do not wish to be limited or restricted to the specific details herein set forth, but wish to reserve to myself any variations or modifications that may appear to those skilled in the art and fall within the scope of the following claims.

Having described my invention, I claim:

1. A head applicable to a well casing including, a base plate with a casing opening, a tubular body spaced above the plate and including a sleeve portion directly over the casing opening, the upper end of the casing extending upwardly through the opening in the plate, the lower end of the sleeve portion being fully exposed at the exterior of the head and being a substantial distance above the plate for the reception of a weld to weld the sleeve portion on the casing, and means spaced from the lower end of the sleeve connecting the plate and body.

2. A head applicable to a well casing including, a base plate with a casing opening, a tubular body spaced above the base plate and including a sleeve portion directly over the casing opening in the plate and engageable over the end of the casing, the upper end of the casing extending upwardly through the opening in the plate, the lower end of the sleeve portion being fully exposed at the exterior of the head and being a substantial distance above the plate for reception of welding entirely around the casing engaged in the sleeve, and means connecting the base and body including ribs spaced from the lower end portion of the sleeve.

3. A head applicable to a well casing including, a base with a casing opening, a tubular body supported above the base and including a sleeve portion directly over the casing opening in the plate and engageable over the end of the casing, the upper end of the casing extending upwardly through the opening in the plate, the lower end of the sleeve portion being fully exposed at the exterior of the head a substantial distance above the plate, welding material joining the lower end of the sleeve portion to the casing, the base being spaced from the body by connecting ribs and having an edge spaced from the sleeve and spaced below the lower end of the body engageable with the casing for reception of welding on the casing.

4. A head applicable to a well casing including, a base plate with a casing opening, a tubular body spaced above the base plate and including a depending sleeve portion directly over the casing opening in the plate and engageable over the end of a casing, the upper end of the casing extending upwardly through the opening in the plate, the lower end of the sleeve portion being fully exposed at the exterior of the head and being a substantial distance above the plate for 10 reception of welding to weld the sleeve portion on the casing, and means connecting the base and body including vertically disposed ribs spaced apart circumferentially of the head and spaced radially from the casing and the said end of the sleeve.

5. In combination two elements, one a tubular body applicable to the upper end portion of a casing and having a downwardly facing portion fully exposed at the exterior of the body for welding to the casing, the other a base plate having a casing opening and engageable around the casing at a point spaced below the body, one element having vertical ribs projecting to the other element, and welding material joining the 20 elements spaced one from the other.

6. A head applicable to a well casing including, a base plate with a casing opening, a tubular body spaced above the plate and including a sleeve portion directly over the casing opening in the plate and engageable over the end of a casing, the upper end of the casing extending upwardly through the opening in the plate, the lower end of the sleeve portion being fully exposed at the exterior of the head a substantial 25 distance above the plate for welding to the casing, and means connecting the base and body including vertical ribs projecting upwardly from the base and welded to the body and spaced from

15
20
25

the casing and from the lower end portion of the sleeve.

7. A head applicable to a well casing including, a base plate with a casing opening, a tubular body spaced above the plate and having a sleeve portion directly over the casing opening in the plate and engageable over the end portion of the casing, the upper end of the casing extending upwardly through the opening in the plate, the lower end of the sleeve portion being fully exposed at the exterior of the head a substantial distance above the plate and a flange portion projecting radially from the upper part of the sleeve portion, the base plate having a weld receiving edge engaging the casing at a point spaced below the sleeve, welding material joining said edge of the plate to the casing, and ribs projecting upwardly from the base and engaging under the flange portion of the body and welded thereto, the ribs being spaced radially from the sleeve.
